LACE

Arthur Wright, Forest Hills, N. Y.

Application August 1, 1941, Serial No. 404,994

8 Claims. (Cl. 24—143)

My invention relates particularly to a lace adapted to retain its position when tied. These laces are particularly applicable for use in shoes but may be used wherever desired.

The object of my invention is to provide a lace which will reduce the tendency to form knots when being untied and which, furthermore, is so constructed as to retain a bow-knot in place so as to not become untied unintentionally. In laces as hitherto made there have been two distinct disadvantages. One is the tendency of the bow-knot to become untied and the other is the tendency to become knotted when the bow-knot is being untied in the usual way by pulling on one of the free ends of the lace. The object of my invention is to construct shoe laces as to obviate both of these disadvantages. In untying a bow-knot by pulling on a free end of the lace in the usual way a hard knot will result if a free end of the lace has inadvertently passed through one of the loops to the other side of the lace. With laces constructed as hereinafter described the free end of the lace is made stiff so that it will not, due to its limpness, fall through the loop to the other side of the lace, and, accordingly, the end of the lace will remain in position on the side of the loop where it was originally located when the bow-knot was tied, so that when a free end of the lace is pulled the bow-knot will become untied without forming a knot. Stiffening throughout the length of the lace would be distinctly disadvantageous, however, as it would make the formation of the loop and knot difficult. Another object is to apply means to prevent slipping of the lace in the bow-knot, so as to prevent the unintentional untying of the knot. Further objects of my invention will appear from the detailed description of the same hereinafter.

While my invention is capable of embodiment in many different forms, for the purpose of illustration I have shown only certain forms thereof in the accompanying drawing, in which—

Fig. 1 is a longitudinal section of a flat tubular lace made in accordance with my invention, shown in a bow-knot;

Fig. 2 is a plan view of a modified form thereof showing a flat tubular lace having its free ends stiffened with straight staples;

Fig. 3 is a side elevation of the same; and

Fig. 4 is a plan view of a lace such as shown in Figs. 2 and 3, but with staples having a wavy form due to lateral turns in the staples in the plane of the lace to retain the staples better in position.

In carrying out my invention, referring first to Fig. 1, I have shown the usual type of flat tubular woven textile fibre shoe lace 1 having two metal tips 2, one on each end thereof. The metal tip 2 is comprised of a thin sheet of metal formed into a cylinder by folding the free edges of the metal cylindrically until the edges of the sheet metal are adjacent or overlapping in the usual way. The free end of the shoe lace at each end of the latter, in accordance with my invention, may be provided with a stiffening element 3 in the form of a flexible rod, such as any kind of bristle, but which is preferably comprised of a thick Nylon bristle from $\frac{1}{64}$ to $\frac{1}{32}$ " in diameter, extending from the outer end of the tip 2 within the tubular flat lace 1 to some point between the fold of a loop 3a of the shoe lace when formed into the bow-knot and the outer end of the tip 2. In other words, the bristle 3 stiffens the free end of the shoe lace between the fold of the loop of the bow-knot and the tip 2, while the remainder of the shoe lace not comprising the free ends thereof remains unstiffened so as not to interfere with the formation of the bow-knot.

Fig. 2 shows a modification of the invention in which the shoe lace 1, having the tip 2, is provided, the same as in Fig. 1, but in which the stiffening of the free ends of the shoe lace is attained by introducing along the free ends of the shoe lace, instead of the bristle 3, a series of staples 4 having rod-like bodies, which may be introduced through the shoe lace from one or the other of the flat sides thereof by a stapling machine so that the free ends 5 of the staples become embedded within the body of the shoe lace 1. In this way the ends of the staples will not catch on the fingers but at the same time the free ends of the shoe lace are stiffened so as to prevent the ends of the lace from falling through the loops and the unintentional knotting of the lace when the bow-knot therein is being untied by pulling on the free end of the lace. At the same time, however, when the lace, as shown in Figs. 2 and 3, is tied into a bow-knot with a knot 6 of the bow located at some point along the series of staples 4. The protuberances formed by the series of staples will hold the knot in place and prevent the free ends of the shoe lace working accidentally towards the untied position of the loop.

In Fig. 4 I have shown another embodiment, which is the same as that shown in Fig. 3 except that in this instance staples 7 are used having two lateral wavy offsets 8 and 9 which tend to

hold the staples 1 fixedly in position to prevent their turning axially and thus make the protuberances formed by the staples more effective in holding the ends of the shoe lace in place in the bow-knot formed therein.

Instead of the stiffening of the end of the shoe lace by the rod 3 or staples 4 or 7 I may stiffen the same portion of the shoe lace, but with not so much advantage as in connection with the forms previously described herein, by impregnating or coating the same end portions of the shoe lace with or without the presence of the rod 3 or staples 4 or 7, with any suitable material, as for example liquid shoe polish, a colored collodion solution or a melted wax such as paraffin, beeswax, etc., while leaving the remainder of the lace without any coating or impregnation. This will also have a water-proofing effect, by covering the staples 4 or 1 for example, in addition to the stiffening of the ends of the shoe lace.

In the operation of the laces which, as above pointed out, may be used in shoes or for any other desired purpose, the various embodiments of the invention will, due to the stiffening of the shoe lace between the fold of the loop and the end of the lace, keep the end of the lace extended so as to retain its original position and prevent its falling through the loop of the lace, so that when the end of the lace is pulled to untie the loop it will not form a hard knot. Also, the protuberances on the staples prevent the shoe laces becoming unintentionally untied. Accordingly, when using the laces constructed as above the annoyance and inconvenience due to the shoe laces becoming inadvertently untied or becoming tied into hard knots when being untied, are obviated.

However, it will be noted that the bristles and staples are not equivalent inasmuch as the staples, due to their protuberances, prevent the unintentional untying of the bow-knot.

While I have described my invention above in detail I wish it to be understood that many changes may be made therein without departing from the spirit of the same.

I claim:

1. An article of manufacture, comprising a lace having tips thereon and having stiffening elements in the form of a series of staples located along each of the free ends of the lace which

are separated by an unstiffened portion of the lace.

2. An article of manufacture, comprising a lace having tips thereon and having stiffening elements in the form of a series of staples forming protuberances located along each of the free ends of the lace which are separated by an unstiffened portion of the lace each of the staples having its ends bent inwardly so as to be directed toward each other.

3. An article of manufacture, comprising a lace having tips thereon and having stiffening elements in the form of a series of laterally-waved staples located along each of the free ends of the lace which are separated by an unstiffened portion of the lace each of the staples having its ends bent inwardly so as to be directed toward each other.

4. An article of manufacture, comprising a lace having tips thereon and having stiffening elements in the form of a series of laterally-waved staples forming protuberances located along each of the free ends of the lace which are separated by an unstiffened portion of the lace each of the staples having its ends bent inwardly so as to be directed toward each other.

5. An article of manufacture, comprising a lace having tips thereon and having stiffening elements in the form of a series of staples located along a free end of the lace.

6. An article of manufacture, comprising a lace having tips thereon and having stiffening elements in the form of a series of staples forming protuberances located along a free end of the lace, each of the staples having its ends bent inwardly so as to be directed toward each other.

7. An article of manufacture, comprising a lace having tips thereon and having stiffening elements in the form of a series of laterally-waved staples located along a free end of the lace, each of the staples having its ends bent inwardly so as to be directed toward each other.

8. An article of manufacture, comprising a lace having tips thereon and having stiffening elements in the form of a series of laterally-waved staples forming protuberances located along a free end of the lace, each of the staples having its ends bent inwardly so as to be directed toward each other.
